US00D835374S

(12) **United States Design Patent** (10) Patent No.: **US D835,374 S**
(45) Date of Patent: **** Dec. 4, 2018**

(54) **TRASH CAN**(71) Applicant: **simplehuman, LLC**, Torrance, CA
(US)(72) Inventors: **Frank Yang**, Rancho Palos Verdes, CA
(US); **Myk Lum**, Irvine, CA (US);
Adam Wade, Rancho Santa Margarita,
CA (US)(73) Assignee: **simplehuman, LLC**, Torrance, CA
(US)(**) Term: **15 Years**(21) Appl. No.: **29/610,345**(22) Filed: **Jul. 11, 2017**

Primary Examiner — Cynthia Ramirez

(74) Attorney, Agent, or Firm — Knobbe, Martens, Olson & Bear, LLP

(57) **CLAIM**

The ornamental design for a trash can, as shown and described.

DESCRIPTION

FIG. 1 is a top, front, left-side perspective view of a trash can of our design;

FIG. 2 is a top, rear, left-side perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.

The broken lines in the figures are to show portions of the trash can and form no part of the claimed design.
